UNITED STATES PATENT OFFICE.

JACOB SIMPSON, OF WASHINGTON, DISTRICT OF COLUMBIA.

PRINTING-PLATE-TRIMMING MACHINE.

1,394,765.

Specification of Letters Patent. Patented Oct. 25, 1921.

Application filed February 20, 1919. Serial No. 278,928.

To all whom it may concern:

Be it known that I, JACOB SIMPSON, a citizen of the United States, residing at Washington, in the District of Columbia, have invented a new and useful Printing-Plate-Trimming Machine; and I do hereby declare the following to be a full, clear, and exact description of the invention, such as will enable others skilled in the art to which it appertains to make and use the same.

The present invention relates to a machine for trimming the edges of printing plates, electrotypes, or the like, and has for its object to provide a device of this character which embodies novel features of construction whereby these plates can be accurately and quickly trimmed in large quantities, thereby bringing about a large saving in both time and labor and enabling the work to be done at considerably less expense than is possible with any of the trimming machines which have heretofore been designed and used for this purpose.

Further objects of the invention are to provide a printing plate trimming machine in which the plates are accurately positioned with respect to the type matter thereon and subsequently acted upon by adjustably mounted cutters which have an operative connection with the positioning means so that they are automatically set in proper relative position by the adjustment of the positioning means to fit the plate, and to provide a machine which simultaneously trims all the edges of the plate while it is securely clamped in position, thereby insuring accuracy and reducing the time of finishing a plate.

Still further objects of the invention are to provide a machine of this character in which the movements of the plate through the machine are entirely automatic after it has been initially fed thereto, which holds the plate rigidly clamped in one position during the entire cutting operation, and thereby avoids the necessity of shifting the position of the plate with the resultant possibility of slipping and miscutting, and which provides for trimming the plates while in an angular position so that the chips from the cutters will be discharged from the machine by the action of gravity and will not clog the machine or interfere with the action of the cutters.

The invention still further aims to pro-

vide a power driven trimming machine of this character which is substantially continuous in its operation, which can be operated by a single person, and which is at all times under the perfect control of the operator.

With these and other objects in view, the invention consists in certain novel combinations and arrangements of the parts such as will more fully appear as the description 65 proceeds, the novel features thereof being pointed out in the appended claims.

For a full understanding of the invention, reference is to be had to the following description and accompanying drawings, in 70 which:

Figure 1 is a side elevation of a printing plate trimming machine constructed in accordance with the invention, a portion of the conveyer which receives the finished 75 plates being broken away.

Fig. 2 is an enlarged vertical sectional view through the upper portion of the machine, showing the plate clamping means and the cutters for trimming the plates. 80

Fig. 3 is a rear view of the printing plate trimming machine, portions being broken away and shown in section.

Fig. 4 is a detail view of the toggle action plate clamping means. 85

Fig. 5 is a plan view of the cutters and adjusting and driving means therefor, all of the cutter support with the exception of one corner thereof being broken away.

Fig. 6 is a top plane view of the feeding 90 table and plate centering means, the latter being shown in operative engagement with a plate by full lines, and by dotted lines as retracted into an inoperative position.

Fig. 7 is a vertical sectional view through the table, taken on the line 7—7 of Fig. 6, and showing the means for actuating one pair or set of the plate centering fingers. 95

Fig. 8 is a vertical sectional view through the table, taken on the line 8—8 at right 100 angles to 7—7 and showing the means for actuating the other pair or set of plate centering fingers.

Fig. 9 is a transverse vertical sectional view through the table on the line 9—9 of 105 Fig. 6, showing the operative connection between the mechanism illustrated by Fig. 8 and the adjusting shaft for a corresponding pair of cutters.

Fig. 10 is an enlarged sectional view 110

through one of the plate centering fingers, taken on the line 10—10 of Fig. 6, and showing the adjustable mounting of the finger.

Fig. 11 is a sectional view on the line 5 11—11 of Fig. 10, showing the pivotal connection between the finger proper and the plate or arm carrying the same.

Fig. 12 is an enlarged detail view of a cam member which is arranged upon the table 10 for automatically lifting the end positioning fingers when they are retracted, thereby enabling an untrimmed printing plate to be inserted in position upon the carrier block. This figure is taken upon the line 12—12 of 15 Fig. 6.

Fig. 13 is a diagrammatic view of the cutters and plate centering or positioning means, showing in a diagrammatic manner the relation between the members whereby 20 the positioning of the cutters is automatically controlled by the movements of the plate positioning fingers as they are brought into engagement with the type matter of the plate.

Fig. 14 is a detail view of the cam means 25 for automatically locking the plate upon the carrier and releasing it therefrom at proper times.

Fig. 15 is an enlarged sectional view on 30 the line 15—15 of Fig. 14, showing an adjustable stop member which can be moved to prevent the automatic release of the plate when it is desired to bring the plate back 35 into position for inspection after it has been trimmed.

Fig. 16 is a detail view of the cam mechanism for oscillating the pivoted plate carrier to bring the plates into the 45° plane of the cutters after they have been centered and 40 clamped upon the carrier.

Fig. 17 is a detail view of the cam means 45 for moving the cutters rectilinearly along the sides of the plate to simultaneously trim all four edges of the plate while it is firmly clamped in position upon the carrier.

Figs. 18 and 19 are detail views of the clutch control device for starting and stopping the machine.

Fig. 20 is a transverse sectional view 50 through the base of the machine, showing the positions of the various cams on the cam shaft.

Fig. 21 is a detail view showing in a diagrammatic manner the pull wire connection 55 between the foot control pedal and the plate centering elements.

Fig. 22 is an enlarged plan view of the auxiliary trimming table which is mounted at the back of the machine and upon which 60 odd sizes of plates are adapted to be trimmed by hand.

Fig. 23 is an enlarged transverse sectional view through the table, taken on the line 23—23 of Fig. 22.

65 Corresponding and like parts are referred

to in the following description and indicated in all the views of the drawings by the same reference characters.

While the idea of the invention is susceptible of being carried out in machines of 70 many different types, one possible embodiment of the invention which will serve for illustrative purposes has been shown by the accompanying drawings. Specifically describing this particular embodiment of the 75 invention, the reference numerals 1 designate the main side frames upon which the plate trimming mechanism is mounted, said side frames being similar in construction and having a spaced and opposed relation to each 80 other. A feed table 2 which is horizontally disposed and arranged in a position convenient to the operator is provided at the front of the frame. A carrier block 3 is movable through an opening 4 in the feed 85 table, and the printing plate or electrotype A which is to be trimmed is first properly centered or positioned upon the carrier block 3, and then tightly gripped between the carrier block 3 and a clamping block 5, said 90 carrier and clamping blocks being arranged upon a pivotally mounted carrier frame B. (See Fig. 2.) This frame has substantially the form of a split ring, being constructed of segmental side pieces 6 which have the 95 body portions thereof spaced and provided with radially disposed arms 7 which are pivoted upon stub shafts 8 projecting from the main frames 1 (see Fig. 3), while the ends of the side pieces 6 terminate respectively in the opposed and substantially tangentially arranged sleeves 9 and 10.

The carrier block 3 is formed with a downwardly extending plunger 11 which is 100 slideable within the sleeve 9, said plunger being formed in two sections which have a wedge 12 interposed between the same so that the effective length of the plunger can be adjusted by moving the wedge in and out. This wedge is operatively connected to an 105 adjusting screw 13 which provides a means for moving the wedge in and out and locking it in an adjusted position. A toggle link 14 is interposed between the lower end of the plunger 11 and a laterally recessed toggle 115 shaft 15 which extends transversely through the sleeve 9 (see Fig. 4). With this construction it will be obvious that by rotating this shaft 15 the toggle link 14 can be brought into alignment with the axis of the sleeve, as 120 indicated by Fig. 2, or permitted to assume an oblique position, as indicated by Fig. 4. In the position shown by Fig. 2 the plunger 11 is moved upwardly and the carrier block 125 correspondingly moved so that the plate A is securely clamped between the carrier block and the clamping block 5. With the position of the toggle link 14 indicated by Fig. 4 the carrier block is permitted to drop away from the clamping block so as to re- 130

lease the electrotype plate A or permit of the insertion of an untrimmed electrotype plate between the members. The clamping block 5 is shown as carried by the head 16 of a yieldably mounted plunger 17 which extends through the upper sleeve 10 of the carrier frame B. A coil spring 18 surrounds the plunger 17 and is interposed between the head of the plunger and a tubular guide 10 plug 19 which is threaded into the upper end of the sleeve. This coil spring 18 holds the plunger yieldably in position, and a nut 20 which is threaded upon the upper end of the plunger limits the outward movement of the plunger under the action of the spring, as well as provides a means for adjusting the plunger.

After a printing plate or electrotype A has been centered upon the carrier block 3 by means of mechanism to be hereinafter described, the toggle shaft 15 is rocked to bring the toggle link 14 into a vertical position, as indicated by Fig. 2, whereupon the carrier block is raised and the plate securely 25 clamped between the carrier block and the clamping block. The carrier frame B is next rotated about its axis to swing the carrier block and clamped electrotype plate A upwardly into the plane of the cutters.

30 In the present instance the cutting mechanism, as shown more clearly by Fig. 2, is arranged in a plane at 45° to the horizontal, this being desirable for the reason that the cuttings will drop away from the plates by 35 the action of gravity and will not clog the cutters. A further advantage of this angular position of the cutters is that after the plates have been trimmed they can be released and permitted to drop by gravity 40 into suitable receiving pockets provided upon a carrier which is driven in synchronism with the rest of the machine. There are four rotary cutters 21 which are arranged to trim the four edges of a rectangular plate at the same time, thereby avoiding 45 the possibility of slipping or error which is incident to the use of a trimming machine in which the plate must be unclamped from one position and reclamped in another position 50 between successive trimming operations upon different edges thereof. The cutters 21 are rigidly applied to the inner ends of cutter shafts 22 which are journaled upon carriages 23, said carriages being slidably 55 mounted upon the lower faces of slides 24 and arranged to move in a direction parallel to the axes of the respective cutter shafts. The cutters 21 of each opposed pair of cutters can thus be moved toward and away 60 from each other and adjusted for operation upon a smaller or a larger plate, as may be desired. The slides 24 are provided upon their upper faces with dove-tail tongues 65 which are slidably received within corresponding guideways or grooves 26 formed

in the lower face of the inclined cutter supporting plate 27. These guide grooves 26 are arranged in two parallel pairs which intersect at the corners of a rectangular figure, thereby enabling the slides 24 to be simultaneously moved rectilinearly along the four sides of a rectangular figure.

70 The slides 24 are each transversely recessed to receive a cutter drive shaft 28 which is geared by 45° worm threads 28a 75 with corresponding threads 22a on the respective cutter shafts 22. The worm threads 28a extend substantially throughout the entire length of the drive shafts 28 so that the shafts 28 and 22 will remain in mesh with each other throughout the entire path of travel of the slides 24. These cutter drive shafts 28 are positioned at the four sides of the cutting mechanism and are all intergeared by the bevel gearing 29. One of the 80 shafts 28 is extended and connected by bevel gearing 30 to a rearwardly extending horizontal drive shaft 31. Said shaft 31 is shown as having a belt and pulley connection 32 with the main drive shaft 33 so that it is always rotating. Rotary motion is thus transmitted at all times to the rotary cutters 21, so that the latter are continuously driven when the machine is in operation.

85 The outer end of each of the carriages 23 is provided with a rack 34 which meshes with a long pinion 35. These pinions 35 extend transversely through suitable guide openings formed in the slides 24 and the teeth of the pinions are sufficiently long to 90 remain in mesh with the racks 34 throughout the entire limit of the movements of the slides 24. These pinions 35 provide a means for moving the carriages 23 in and out to adjust the cutters 21 toward and away 95 from each other, thereby properly positioning the cutters to operate upon a large or a small size of plate as may be desired. In this connection it will be noted that the 45° worm threads 22a on the cutter shafts 100 23 are sufficiently long to remain in mesh with the worm threads 28a of the worm shafts 28 throughout the in and out adjustment of the cutters. These long pinions 35 and cutter drive shafts 28 are suitably journaled in bearings (not shown) projecting from the cutter supporting plate 27, and it will be obvious that the four cutters are continuously driven from the short drive shaft 31, and that by manipulating the long pinions 35, by mechanism to be hereinafter described, the cutters can be moved in and out and adjusted for proper operation upon the particular plate or plates to be trimmed.

105 Each of the cutter carrying slides 24 is 115 provided upon the inner edge thereof with a rack bar 36, said rack bars meshing with teeth 37 upon a ring or annulus 38 mounted upon a neck 39 which surrounds a central opening 40 in the inclined cutter supporting 120 130

plate 27. A circular plate 41 which is detachably secured to the lower end of the neck 39 retains the ring 38 in position upon the neck. The upper portion of the carrier frame B extends through the central opening 40 of the cutter supporting plate 27 and said opening provides a sufficient amount of clearance space so that there is nothing to interfere with the oscillation of the carrier frame as it is rotated to swing the carrier block 3 up and down.

The upper face of the ring or annulus 38 is provided with bevel teeth 42 which mesh with a bevel gear 43, said gear projecting through an opening 44 in the inclined cutter supporting plate 27, and being rigid with a short horizontal shaft 45 which is journaled within bearings 46 at the top of the machine. The outer end of the shaft 45 is provided with a pinion 47 which meshes with a rack 48 at the upper end of a cam actuated rod 49, a guide 50 being provided to hold the rack in operative engagement with the pinion at all times (see Fig. 1). The four cutters 21 are initially located at what would be the respective corners of the rectangular plate to be trimmed. Upon either the upward or downward movement of the cam actuated rod 49 the rack 48 rotates the pinion 47 and bevel gear 43, thereby turning the ring 38 on the neck 39 and operating through the rack bars 36 to move the slides 24 rectilinearly. The cutters thus have a progressive movement along the four sides of the plate from one corner to the adjacent corner, and each cutter thus completely trims one edge of the plate. It will also be obvious that owing to this progressive movement of the cutters they do not conflict with each other at the corners of the plate, and a clear cut trimming action is obtained around the entire periphery of the plate. Upon the upward movement of the cam actuated rod 49 the slides 24 are moved to shift the cutters rectilinearly along the periphery of the plate in one direction, this direction of movement being reversed for the next plate to be trimmed upon the downward movement of the cam actuated rod 49.

After the plate has thus been trimmed it is released by a movement of the toggle clamping means, and slides by gravity down an inclined chute 51 which is arranged immediately under the cutters. The lower part of the chute is formed by longitudinal wires or rods 52 and the cuttings or shavings fall through these wires (see Figs. 2 and 3) into a suitable receptacle, not shown, provided to receive the same, while the trimmed plates slide down the wires 52 and are deposited into the pockets 53 of an endless carrier 54 which is arranged at the back of the machine. The receiving carrier 54 extends around drums 55, only one

of which is shown. This drum is provided with a ratchet wheel 56 which is engaged by a pawl 57 upon a plate 58 loose upon the shaft of the drum. A link 59 loosely connects the plate 58 to the carrier frame B so that as the carrier frame is oscillated back and forth upon its axis, a step by step movement is imparted to the receiving carrier 54 through the action of the pawl and ratchet mechanism. The pockets 53 of the receiving carrier are thus brought successively into position to receive the trimmed printing or electrotype plates A as they are discharged from the carrier. The metal chips or shavings dropping from the cutter fall through the wires 52, as previously explained, and are directed by a spout 60 (see Figs. 1 and 2) into a suitable receptacle provided for that purpose. A very great advantage incident to locating the cutting mechanism in a 45° plane is that the cuttings fall away from the cutters by the action of gravity and are thereby prevented from clogging the cutters and interfering with the proper action thereof.

Extending horizontally under the feed table 2 and arranged on opposite sides of the opening 4 therein is a pair of adjusting shafts 61 and 62. These shafts have a parallel relation to each other and are provided at their outer ends with hand wheels 63. The adjusting shaft 61 has an operative connection with the upper and lower cutters 21 for the purpose of simultaneously moving the said cutters toward and away from each other. The inner end of the said shaft 61 is shown as provided with a worm 64 which meshes with a worm wheel 65 on the shaft of the lower one of the transversely disposed long pinions 35 (see Figs. 2 and 13). It will thus be obvious that by rotating the shaft 61 the lower pinion 35 can be rotated to move the lower cutter 21 in and out. A corresponding motion is imparted to the upper cutter 21 by means of a rack bar 66 which is provided at its respective ends with upwardly and downwardly facing rack teeth 66a meshing with pinions 67 on the shafts of the upper and lower long pinions 35. The upper and lower long pinions 35 are thus operatively connected so as to be rotated a corresponding amount in a reverse direction upon any movement of the adjusting shaft 61. The upper and lower cutters 21 can thus be moved toward and away from each other and properly adjusted to trim the edges of the electrotype plate A when the latter is swung upwardly into position to be trimmed.

The other adjusting shaft 62 is somewhat shorter than the shaft 61 (see Fig. 13) and terminates at its inner end in a worm 68 which meshes with a worm wheel 69 on a transverse shaft 70. This shaft is provided at points toward its opposite ends

with pinions 71 which engage rack teeth 72^a at the lower end of a pair of rack bars 72. These rack bars are inclined upwardly and provided at their upper ends with rack teeth 72^b facing in directions at right angles to the teeth 72^a. These upper sets of teeth 72^b on the rack bars 72 face in opposite directions and mesh with pinions 73 on the shafts of the inclined long pinions 35 at the 10 sides of the machine. These side pinions 35 are thus geared together to be rotated a corresponding amount in reverse directions upon rotation of the adjusting shaft 62. The two side cutters 21 can thus be moved 15 toward and away from each other and properly adjusted to act upon the particular plate or plates to be trimmed. The rack bars 72 may be held in operative engagement with the respective pinions by idlers 20 74 which engage the backs of the rack bars at points adjacent to the pinions.

At the end of each cycle of operation and preparatory to the beginning of a new cycle of operation the carrier frame B is rotated 25 to swing the carrier block 3 downwardly into the central opening 4 of the feed table 2. A new printing or electrotype plate A which it is desired to trim is then placed upon the carrier block 3 and properly centered thereon by means of the two sets of 30 positioning fingers 75, 75 and 76, 76, respectively (see Figs. 6 to 8 inclusive). The opposed positioning fingers 76 are mounted at their ends between arms 77 which extend 35 upwardly through transverse slots 78 in the feed table. The corresponding arms 77 at opposite sides of the opening in the feed table are carried by corresponding slides 79 and 80 which are engaged under the feed 40 table. One pair of these slides 79 and 80 is provided at each side of the opening in the feed table, and the slides of each pair have a superposed relation, being mounted within suitable guides 81 so that they are free to 45 slide back and forth longitudinally (see Fig. 8). At one end the slides 79 and 80 are provided with opposed racks 82, the two sets of racks being engaged by pinions 83 on a shaft 84 which extends transversely of the 50 slides and is journaled within suitable bearings 85. The right hand end of this shaft 84 is provided with a pinion 86 which meshes with the teeth 87 of a rack 88, said rack bar being arranged over the adjusting 55 shaft 61 and in parallel relation thereto. The rack bar is directed in its sliding movements by a guide 89, and one end thereof has a yielding connection with a block 90 threaded upon the adjusting shaft 61. The 60 adjusting shaft 61 is held against longitudinal movement, as by means of flanges 91 thereon which engage opposite sides of the member 89, and it will be obvious that as the adjusting shaft is rotated the block 90 will be moved in and out thereon. This

will result in a longitudinal movement of the rack bar 88, which will in turn rotate the shaft 84 and move the slides 79 and 80 to adjust the fingers 76 toward and away from each other. In adjusting the device 70 the printing or electrotype plate A is placed upon the carrier block 3 and the adjusting shaft 61 rotated to bring the positioning fingers 76 into engagement with the type matter on the plate. The relation of the 75 parts is such that the upper and lower cutters 21 are moved toward and away from each other simultaneously and in synchronism with the positioning fingers 76. When these positioning fingers 76 are brought into 80 engagement with the type face of the printing plate by manipulating the adjusting shaft 61 the upper and lower cutters 21 are simultaneously brought into exactly the proper position for trimming the corresponding edges of the plate when it is swung upwardly into position to be acted upon by the cutters.

The other pair of positioning fingers 75 are carried by arms 92 which are hingedly 90 connected at their ends, as indicated at 93, to slides 94 arranged within longitudinal guideways 95 formed in the inner edge of the feed table 2. These upper slides 94 are connected by stems 96 to upper and lower 95 longitudinally extending slides 97 and 98, respectively. These slides 97 and 98 operate within a suitable guide 99 and are provided with opposed sets of rack teeth 100 which mesh with an interposed pinion 101, thereby 100 providing for a corresponding movement in reverse directions of the upper and lower slides. The lower slide 98 is provided at one end thereof with an extension 98^a having a nose 102 at the end thereof, a coil spring 103 being interposed between said nose and a guide member 104. A cam plate 105 is arranged upon the rack bar 72 at the left hand side of the device and the inclined edge of this cam plate extends into the path of the 110 nose 102. It will be remembered that the two rack bars 72 are moved up and down by the rotation of the other adjusting shaft 62 to position the side cutters 21. In adjusting the device the fingers 75 are brought into engagement with the type matter of the electrotype plate, and the nose 102 of the lower slide 98 thereby caused to assume a definite position. The other adjusting shaft 62 is 115 then manipulated until the rack bars 72 are brought into such a position that the inclined face of the cam plate 105 engages the nose 102. The relation between the members is such that the side cutters 21 are then accurately positioned to trim the sides of the 120 electrotype plate when the latter is swung upwardly into position for cutting. The positioning fingers 75 are shown as having a hinge connection 106 (see Figs. 10 and 11) with plates 107 which are adjustably 130

mounted upon the ends of the arms 92. The hinge connections 106 can be tightened by screws 108 so that the positioning fingers are held in an adjusted position, although it will be obvious that they can be moved up and down to accommodate different thicknesses of plates. The plates 107 to which the fingers are thus connected extend transversely with respect to the arms 92 and have a sliding engagement with the top thereof. Clamping screws 109 extend through slots 110 in the plates and are threaded in the arms 92, said screws providing a means for locking the plates in an adjusted position. The outer ends of the plates are flanged and provided with adjusting screws 111 which have a threaded engagement with the arms 92 and provide a means for moving the plates in and out to adjust the positioning fingers when the clamping screws 109 are loosened. This manner of mounting the positioning fingers 75 provides for adjusting the position thereof upon the arms by which they are carried.

25 A pull cable 112 is provided for retracting the positioning fingers 75 and 76 and withdrawing the same from the opening 4 in the feed table after the plate has been properly centered upon the carrier block, and preparatory to moving the carrier block through the opening to bring the plate into the plane of the cutters. The pull cable 112 passes around a number of suitable guide pulleys 113 and has the lower end thereof attached 30 to a foot control pedal 114, while the upper end thereof terminates in two branches 112^a and 112^b. These branches are carried around pulleys 115 arranged under the feed table 2 and extend in directions at right angles to each other, the branch 112^a being connected to the lower slide 98 of the two slides 97 and 98 which control the movements of the plate positioning fingers 75, while the branch 112^b is connected to the rack bar 88 which is 35 mounted to be moved longitudinally by rotation of the adjusting shaft 61 (see Fig. 21). This rack bar 88 is slideable through the nut or block 90, being provided with set collars 116 to limit the movements thereof.

40 50 A spring 117 surrounds the rack bar 88 and is interposed between the nut 90 and one of the collars 116 (see Fig. 9). When there is no tension in the pull wire or cable 112 the rack bar 88 is movable with the nut or block 90 and operates as previously described to 55 adjust the positioning of the plate centering fingers 76 as the shaft 61 is rotated. However, the rack bar 88 can be moved longitudinally against the action of the spring 117 when a sufficiently strong pull is exerted thereon through the branch cable 112^b. It will thus be obvious that when the foot control pedal 114 is moved downwardly the two sets of plate positioning fingers 75 and 76 60 will be retracted into inoperative position

and withdrawn from the opening 2 in the feed table. When the positioning fingers 75 are retracted the arms 92 which support the same ride upon cam lugs 118 (see Figs. 6 and 12) and are thereby swung upwardly 70 into the dotted line position indicated by Fig. 8. This enables a fresh electrotype plate to be readily inserted in position upon the carrier block.

The foot control pedal is slideable upon 75 the lower end of a clutch control lever 119, having a pin and slot connection 120 therewith. The clutch control lever 119 is rigid with a sleeve 121 (see Fig. 19) which is journaled upon a stub shaft 122 projecting from one of the main side frames 1, said sleeve being provided with a segmental plate 123 and also with an arm 124 terminating in a roller 125 which engages the periphery of a cam disk 126. A clutch shifting lever 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670

The clutch shifting lever 127 engages a clutch 131 (see Figs. 1 and 18) which is 110 slideable upon the main drive shaft 33 and movable into and out of engagement with a worm 132 which is loose upon the shaft. This worm 132 meshes with a worm gear 133 which is rigid upon a transversely extending cam shaft 134, said shaft being journaled within suitable bearings provided in the main side frames 1. The before mentioned cam disk 126 is rigid upon this cam shaft 134, as are also the three cams, 135, 136, and 137. The cam 135 controls the locking and unlocking of the plate on the carrier block. The cam 136 controls the swinging of the carrier frame B to raise and lower the carrier block. The cam 137 has an operative connection with the before mentioned cam actuated rod 49 which controls the rectilinear movements of the cutters 21.

The cam 135 which controls the locking 130

and releasing of the printing or electrotype plate upon the carrier (see Fig. 14) is formed with a cam groove having two diametrically opposed low portions 138^a, and 5 two diametrically opposed high portions 138^b, the adjacent ends of the high and low portions of the cam groove being connected by inclined portions 138^c. An upright cam rod 139 which has the lower end thereof 10 slotted at 140 to receive the cam shaft 134 is provided with a roller 141 which rides within the groove of the cam 135. The upper end of this cam rod 139 is pivotally connected at 142 to a plate 143 which is 15 loose upon one of the stub shafts 8 upon which the carrier frame B is journaled. A lever 144 is also loose upon the stub shaft, the upper end of the lever being received between a pair of stops 145 and 146 on the 20 plate 143, while the lower end of the lever is connected by a link 147 to a crank arm 148 on the before mentioned toggle shaft 15 which controls the toggle link 14 of the locking mechanism (see Fig. 4). The link 25 147 is curved so as to clear the opening in the feed table when the carrier frame is swung upwardly.

The position of the parts at the beginning of a cycle of operation is indicated on Fig. 30 14. The roller 141 is at the end of one of the raised portions 138^b of the cam groove, and upon the initial movement of the cam 135 in the direction of the arrow, the roller 141 is caused to travel down one of the inclined 35 portions 138^c of the cam groove into a low portion 130^a of the cam groove. This results in swinging the plate 143, whereupon the lever 144 is moved by engagement of the upper end thereof with the stop 145. 40 This operates through the link 147 and arm 148 to rotate the toggle shaft 15 and swing the toggle link 14 into a vertical position, thereby moving the carrier block upwardly to clamp the printing or electrotype plate 45 firmly in position between the said carrier block and the clamping block 5. The plate remains clamped upon the carrier block while the carrier frame is rotated to swing the carrier block and plate upwardly into 50 the 45° plane of the cutters, and the two stops 145 and 146 of the plate 143 are spaced 45° apart so that when the carrier block 3 is in a raised position the upper end of the lever 144 is moved over against the stop 55 member 146, as indicated by dotted lines on Fig. 14. At the completion of the cutting operation the roller 141 is brought into the other raised portion 138^b of the cam groove, thereby moving the cam rod 139 upwardly 60 and swinging the plate 143 back to its original position. This movement of the plate operates through the stop 146 to swing the lever 144 in the necessary manner to rock the toggle shaft 15 and release the 65 plate. The plate being released in the 45°

plane drops by gravity down the chute 51 and slides along the wires 52 into one of the pockets 53 of the receiving carrier 54 (see Figs. 1 and 3).

The stop lug 146 is adjustable, being carried by an arm 149 which is pivoted upon the stub shaft 8 (see Fig. 15). A spring actuated locking plunger 150 is mounted upon the stop 146 and adapted to enter either one of a pair of openings 151 in the plate 143. 70 When the stop 146 is in the position indicated by Fig. 14, the printing or electrotype plate will be released by the action of the cam plate 135 at the completion of the trimming operation. However, when trimming the first plate of a series of plates, it may be desired to have the plate return to the feed table for inspection instead of being released and permitted to slide into a pocket of the receiving carrier 54. When 80 this is desired the spring plunger 150 is withdrawn and the arm 149 swung away from the stop lug 145 to permit the spring plunger to enter the other opening 151. The stop 146 is thus moved away from the lever 144 85 so that the movement of the plate 143 by the cam 135 at the end of the trimming operation will not result in swinging the lever 144 to release the electrotype plate. The trimmed electrotype plate will then be returned to the 90 feed table with the carrier block 3, so that it can be inspected by the operator to ascertain if the adjustment is accurate before feeding the other plates of the series of the machine.

The cam wheel 136 for raising and lowering the carrier block is provided with a cam groove having opposed low portions 152^a and opposed high portions 152^b connected by inclined portions 152^c (see Fig. 16). An upwardly extending cam rod 153 100 has the lower end thereof slotted at 154 to receive the cam shaft 134, while the upper end thereof is pivotally connected at 155 to a short arm 156 projecting from the carrier frame B. A roller 157 on the cam rod 105 travels in the groove of the cam wheel, and the initial position of the parts is indicated by Fig. 16. Upon the initial movement of the cam shaft 134 the roller 157 travels in one of the low portions 152^a of the cam 110 groove, thereby holding the carrier block in a lowered position until the cam 135 shall have acted, as previously described, to clamp the plate in position upon the carrier. The roller 157 then rides in one of the inclined 115 portions 152^c of the cam groove which operates to rotate the carrier frame B and swing the carrier block upwardly into the 45° plane of the cutters, as indicated by dotted lines on Fig. 16. The cam roller 157 120 then rides in one of the raised portions 152^b of the cam groove and locks the carrier block in a raised position until after the cutters have completed the trimming operation and the plate has been released, as previously de- 125 130

scribed. The roller 157 then rides down the inclined portion 152 of the cam groove and rotates the carrier frame to bring the carrier block back to its original position. This completes one cycle of operation, and the parts are again in their original position and ready to receive another electrotype plate.

The cam wheel 137 which controls the rectilinear movement of the cutters is formed with a groove having a low portion 158^a, and a raised portion 158^b, the adjacent ends of the low and raised portions of the cam groove being connected by inclined portions 158^c. The before mentioned cam rod 49 is slotted at its lower end at 49^a to receive the cam shaft 134, and is provided with a roller 159 which operates within the groove of the cam wheel. The position of the parts at the beginning of a cycle is indicated by Fig. 17. When the machine is started into operation the roller 159 travels either in the low portion 158^a or the raised portion 158^b of the cam groove, and there is no up and down movement of the cam rod 49 until the roller 159 is brought into engagement with one of the inclined portions 158^c of the cam groove. This happens after the carrier B has been rotated to swing the plate upwardly into the plane of the cutters, and the vertical movement of the cam rod 49 then operates, as has been previously explained, to move the cutters rectilinearly so that all four edges of the plate are simultaneously trimmed while it is securely clamped in position upon the carrier.

The cam disk 126 which controls the clutch 131 (see Fig. 18) is also rigid upon the cam shaft 134, being provided at diametrically opposite points with notched seats 160 which the roller 125 enters when the clutch is in an open position and the machine is not in operation. A spring actuated plunger 161 engages the arm 124 and normally holds the roller 125 in a yielding contact with the periphery of the cam disk 126. The main drive shaft 33 is connected to a suitable source of power and continuously rotated, motion being transmitted from this shaft 33 through the belt and pulley connection 32 (see Fig. 3) to the upper shaft 31 from which the four cutters 21 are continuously driven.

At the beginning of a cycle of operation the roller 125 of the arm 124 (see Fig. 18) is seated in one of the notches 160 of the cam disk 126 with the clutch 131 in an open position. The operator presses downwardly upon the foot pedal 114 which has a pin and slot connection 120 with the clutch control lever 119, and thereby pulls upon the cable 112 with the result that the plate positioning fingers 75 and 76 are retracted into an inoperative position, the fingers 75

being simultaneously swung upwardly above the surface of the feed table 2 by the action of the cam lugs 118. This enables the operator to place an untrimmed electrotype plate upon the carrier block 3, whereupon the foot control pedal 114 is released and the positioning fingers 75 and 76 permitted to engage the edge of the type matter on the plate. Assuming that there are a number of plates of the same size to be trimmed, and that the cutters and positioning fingers have been previously adjusted by means of the adjusting shafts 61 and 62, as previously described, it will be apparent that when the positioning fingers are released they will operate automatically to center the electrotype plate upon the carrier block in exactly the proper position. The operator then again presses the foot pedal 114 downwardly to retract the positioning fingers 75 and 76 from the opening 4 in the feed table, and presses forwardly upon the pedal, thereby moving a shoulder 163 on the pedal under an arm 164. The pedal 114 is thereby locked in a lowered position with the positioning fingers 75 and 76 withdrawn from the opening in the feed table, and the clutch shifting lever 127 moved to close the clutch 131. At the same time, the roller 125 is lifted out of the notch 160 and caused to ride upon the periphery of the cam disk 126 as the cam shaft 134 with all of the cams thereon starts to rotate, owing to the closing of the clutch and the locking of the worm 132 with the main drive shaft.

With the cam arrangement which has been shown and described, a one-half revolution of the cam shaft is required for each cycle of operation. The cams are arranged in such a relation to each other that the initial movement of the cam shaft 134 causes the cam wheel 135 to lock the plate in position upon the carrier, whereupon the cam 136 comes into action and swings the carrier block upwardly into the 45° plane of the cutters. The cam 137 then comes into action and moves the cutters rectilinearly to trim the plate, after which the plate is released by a further action of the cam wheel 135 and the carrier block lowered to its original position by a subsequent action of the cam wheel 136. This is all accomplished by a one-half revolution of the cam shaft 134, and the roller 125 of the clutch control device then drops into the other notch 160 of the cam disk 126, the two notches 160 being positioned 180° apart. As soon as the roller 125 drops into the notch 160 the clutch 31 is opened and the machine automatically stopped with the parts returned to their original positions. Another plate of the same size as the previous plate can then be placed upon the carrier block and the operation repeated, it being only neces-

sary to readjust the cutters and positioning fingers when there is a change in the size of the plates to be trimmed.

An attachment for trimming by hand odd 5 plates or plates of a larger size than are adapted to pass through the machine is arranged at the back of the device, the short horizontal shaft 31 is provided at the rear end thereof with a cutter 165 which over- 10 hangs the inner edge of a horizontal shelf 166. This shelf is provided with a pair of transversely extending dove-tail grooves 167 and has a slide 168 mounted thereon, said slide being provided with dove-tail tongues 15 169 which are received within the grooves 167. A handle 170 at one end of the slide provides a means for manually moving the slide back and forth in a direction parallel to the face of the cutter in order to trim 20 the edge of a plate A which may be clamped upon the slide. A clamping bar 171 extends across the top of the plate A and has the ends thereof secured to the slide by suitable clamping screws 172. Stop fingers 173 are 25 adjustably mounted upon the clamping bar 171, having a pin and slot connection therewith, and being adapted to be locked in an adjusted position by means of the screws 174. The ends of the stop fingers 173 are 30 bent downwardly at 173^a and adapted to engage the type face of the plate to be trimmed, thereby holding the inner edge of the plate in proper position for trimming by the cutter 165 when the slide 168 with 35 the plate clamped in position thereon is moved transversely across the table or shelf 166. The ends of the plate A are engaged by positioning fingers 175 which are clamped by means of screws 176 to slides 177 mounted 40 in a dove-tail groove 178 in the slide 168. These positioning fingers 175 engage the type face of the plate and coöperate with the clamping bar 171 and stop fingers 173 to hold the plate rigidly in position upon 45 the main slide during the trimming operation.

The portion 51^a of the chute 51 which is located adjacent to the position of the carrier block when the latter is raised is 50 hingedly mounted, as indicated at 180 (see Fig. 2). This hinge 180 has a spring action which normally holds the chute section 51^a yieldably in alignment with the bottom of the chute. However, if it should happen 55 that a plate upon being released does not slide freely down the chute, but stops after partially leaving the carrier block, the hinged portion 51^a of the chute will yield and swing downwardly upon the lowering 60 of the carrier block, thereby preventing breakage of the parts and perhaps serious damage to the mechanism of the machine.

While I have illustrated and described a single form of machine constituting a concrete embodiment of this invention, I am 65

aware that the principle thereof can be carried out in many other forms without departing from the scope of the invention as expressed in the claims, and the device can be used for trimming any kind of plates 70 such as printing plates or electrotypes. Therefore, I do not wish to be limited to the particular mechanism shown and described, since there are many features of the invention which are believed to be 75 broadly new.

Having thus described the invention, what I claim as new and desire to secure by Letters Patent, is:

1. A machine for trimming plates, including a carrier, means for centering a plate upon the carrier at one position of the carrier, and cutters for trimming the plate at another position of the carrier, said cutters being adjustably mounted and being operatively connected with the centering means so as to be automatically positioned in the proper manner for cutting when the plate is centered upon the carrier. 80

2. A machine for trimming plates, including a carrier, means arranged in one plane for centering a plate upon the carrier, means for clamping the plate upon the carrier after it has been centered thereon, and cutters arranged in another plane for trimming the plate at another position of the carrier. 95

3. A machine for trimming plates, including a carrier, means for centering a plate upon the carrier at one position of the carrier, means for clamping the plate upon the carrier, and cutters arranged in an inclined plane to trim the plate at another position of the carrier, the inclination of the cutters causing the cuttings to be discharged by 105 gravity. 100

4. A machine for trimming plates, including a carrier, means for centering a plate upon the carrier at one position thereof, means for clamping the plate upon the carrier, cutters arranged in an inclined plane to act upon the plate at another position of the carrier, means for releasing the plate after being acted upon by the cutters, and gravity discharge means for the released 110 plate. 115

5. A machine for trimming plates, including a carrier, plate positioning elements for centering a plate upon the carrier in one position thereof, means for retracting the 120 plate positioning elements, means for clamping the plate upon the carrier, and cutters for trimming the plate at another position of the carrier.

6. A machine for trimming plates, including a carrier, positioning means for centering a plate upon the carrier at one position thereof, adjustably mounted cutters for trimming the plate at another position of the carrier, and means for obtaining a cor- 125 130

responding adjustment of the cutters and fingers.

7. A machine for trimming plates, including a carrier, adjustable positioning elements

5 for centering a plate upon the carrier at one position thereof, means for clamping the plate upon the carrier, adjustable cutters arranged to act upon the plate at another position of the carrier, means for obtaining a 10 corresponding adjustment of the positioning members and cutters, and means for moving the cutters rectilinearly along edge portions of the plate.

8. A machine for trimming plates, including a carrier, a set of opposed positioning members for centering a plate upon the carrier at one position thereof, means for clamping the plate upon the carrier, a corresponding set of opposed cutters arranged

20 to act upon the plate at another position of the carrier, means for simultaneously and correspondingly adjusting the positioning means and cutters, and means for moving the cutters along edge portions of the plate.

25 9. A machine for trimming plates, including a carrier, a pair of opposed positioning elements for centering a plate upon the carrier, means for retracting the positioning elements into inoperative position, means for

30 clamping the plate upon the carrier, a pair of opposed cutters arranged to act upon the plate at another position of the carrier and movable toward and away from each other, means controlled by the position of the po-

35 sitioning elements for correspondingly adjusting the cutters, and means for moving the cutters along edge portions of the plate.

10. A machine for trimming plates, including a carrier, a set of opposed position-

40 ing elements movable toward and away from each other and serving to center a plate upon the carrier at one position thereof, means for retracting the positioning elements, means for clamping the plate in position

45 upon the carrier, a pair of opposed cutters movable toward and away from each other and arranged in an inclined plane to act upon the plate at another position of the carrier, means controlled by the position of

50 the positioning elements for obtaining a corresponding adjustment of the cutters, means for moving the cutters along edge portions of the plate, means for releasing the trimmed plate while in an inclined position, and a 55 chute discharging the released plate from the machine by the action of gravity.

11. A machine for trimming plates, including a carrier, a set of opposed positioning elements movable toward and away from

60 each other and engaging the plate to center it upon the carrier at one position thereof, a pair of opposed cutters adjustable toward and away from each other and arranged to act upon the plate at another position of the

65 carrier, and an operative connection between

the positioning elements and the cutters for automatically adjusting the cutters when the positioning elements are brought into engagement with the plate.

12. A machine for trimming plates, including a carrier, a set of opposed positioning elements movable toward and away from each other and serving to center the plate upon the carrier at one position thereof, a set of opposed cutters adjustable toward and 75 away from each other and arranged to act upon the plate at another position of the carrier, and a manually operable adjusting member having an operative connection with both the cutters and positioning elements for adjusting the cutters according to the position of the positioning elements when the latter are in engagement with the plate.

13. A machine for trimming plates, including a cutter support, opposed slides movable upon the cutter support in substantially parallel lines, transversely movable carriages mounted upon the slides, cutters carried by the carriages, a carrier for moving the plate to the cutters, means for positioning the plate on the carrier, means controlled by the positioning means for moving the carriages to obtain a corresponding adjustment of the cutters, and means for operating the slides to move the cutters along 80 90 edge portions of the plate.

14. A machine for trimming plates, including a cutter support, opposed slides movable thereon along substantially parallel 100 lines, transversely movable carriages mounted upon the slides, cutter shafts journaled upon the carriages, cutters upon the shafts, means for moving the carriages toward and away from each other to adjust the position 105 of the cutters, a carriage for moving the plate to the cutters, means for operating the slides to move the cutters along edge portions of the plate, and cutter drive shafts extending substantially parallel to the path of 110 the slides and connected to the cutter shafts by gearing which maintains a driving connection between the shafts throughout the limits of movement of the carriages and slides.

15. A machine for trimming plates, including a cutter support, opposed slides movable thereon along substantially parallel lines, carriages mounted upon the slides and adjustable transversely thereof, cutter 120 shafts journaled upon the carriages, cutters upon the cutter shafts and movable toward and away from each other by adjusting the carriages, a carrier for moving the plate to the cutters, means for continuously driving 125 the cutter shafts at all positions of the carriages and slides, means for simultaneously moving the carriages to adjust the cutters, and means for operating the slides to move the cutters along edge portions of the plate. 130

16. A machine for trimming plates, including a cutter support, opposed slides movable thereon along substantially parallel lines, carriages mounted upon the slides and transversely adjustable thereon, cutter shafts journaled upon the carriages, cutters upon the cutter shafts, a carrier for moving the plate to the cutters, gearing for simultaneously moving the carriages to adjust the cutters toward and away from each other, gearing for continuously driving the cutter shafts at all positions of the carriages and slides, racks upon the slides, and gearing engaging the racks for simultaneously operating the slides to move the cutters along edge portions of the plate. 70
17. A machine for trimming plates, including a cutter support, opposed slides movable thereon along substantially parallel lines, carriages mounted upon the slides and adjustable transversely thereof, cutter shafts journaled upon the carriages, cutters upon the cutter shafts, a carrier for moving the plate to the cutters, opposed positioning elements for centering the plate upon the carrier, means controlled by the positioning elements for moving the carriages to obtain a proper adjustment of the cutters, means for continuously rotating the cutters at all positions of the carriages and slides, and means for operating the slides to move the cutters along edge portions of the plate. 80
18. A machine for trimming plates, including a cutter support, opposed slides movable thereon along substantially parallel lines, carriages mounted upon the slides and adjustable transversely thereof, cutter shafts journaled upon the carriages, cutters upon the cutter shafts, a carrier for moving the plate to the cutters, racks upon the carriages, pinions extending parallel to the paths of the respective slides and meshing with the racks, the teeth of the pinions being sufficiently long to remain in mesh with the racks at all positions of the slides, means for actuating the pinions to move the carriages in and out and adjust the position of the cutters, means for continuously driving the cutter shafts at all positions of the carriages and slides, and means for actuating the slides to move the cutters along edge portions of the plate. 95
19. A machine for trimming plates, including a cutter support, opposed slides movable thereon along parallel lines, carriages mounted upon the slides and adjustable transversely thereof, cutter shafts journaled upon the carriages, cutters upon the cutter shafts, racks upon the carriages, pinions extending parallel to the paths of the slides and meshing with the racks, the teeth of the pinions being sufficiently long to remain in mesh with the racks at all positions of the slides, means for actuating the pinions to move the carriages in and out and adjust the 100
20. A machine for trimming plates, including a cutter support, opposed slides movable thereon along substantially parallel lines, carriages mounted upon the slides and adjustable transversely thereof, cutter shafts journaled upon the carriages, cutters upon the cutter shafts, a carrier for moving the plate to the cutters, opposed positioning elements for centering the plate upon the carrier, means controlled by the positioning elements for moving the carriages to obtain a proper adjustment of the cutters, means for continuously rotating the cutters at all positions of the carriages and slides, and means for operating the slides to move the cutters along edge portions of the plate. 110
21. A machine for trimming plates, including a cutter support, opposed slides movable thereon along substantially parallel lines, carriages mounted upon the slides and adjustable transversely thereof, cutters carried by the carriages, means for continuously rotating the cutters at all positions of the carriages and slides, a carrier for moving the plate to the cutters, opposed positioning elements movable toward and away from each other and serving to center the plate upon the carrier, a manually operable adjusting element for moving the carriages to adjust the cutters, and means for gaging the adjustment of the cutters to correspond to the position of the positioning element when the latter are in engagement with the plates. 115
22. A machine for trimming plates, including a cutter support, opposed slides movable thereon along substantially parallel lines, carriages mounted upon the slides and adjustable transversely thereof, cutters carried by the carriages, means for continuously driving the cutters at all positions of the carriages and slides, a carrier for moving the plate to the cutters, a pair of opposed positioning elements movable in and out for centering the plate upon the carrier, an adjusting shaft operatively connected to the carriages for simultaneously moving them in and out to adjust the position of the cutters, and an operative connection between the positioning elements and the cutter adjusting means for gaging the adjustment of the cutters by the position of the positioning elements when the latter are in engagement with the plate. 120
23. A machine for trimming plates, including a cutter support, a pair of opposed slides movable thereon along parallel lines, carriages mounted upon the slides and adjustable transversely thereof, cutters carried 125
- 65

- by the carriages, means for continuously driving the cutters at all positions of the carriages and slides, racks upon the carriages, pinions engaging the racks and remaining in mesh therewith at all positions of the carriages, a carrier for moving the plate to the cutters, a pair of opposed positioning elements movable in and out and serving to center the plate upon the carrier, and a manually operable adjusting element operatively connected with both the pinions and positioning fingers for moving the carriages to adjust the cutters according to the position of the positioning elements.
- 15 24. A machine for trimming plates, including a cutter support, opposed slides movable thereon along substantially parallel lines, carriages mounted upon the slides and adjustable transversely thereof, cutters carried by the carriages, means for continuously driving the cutters at all positions of the carriages, a carrier for moving the plate to the cutters, opposed positioning elements movable toward and away from each other and serving to center the plate upon the carrier, an adjusting shaft operatively connected to both the positioning elements and the carriages for obtaining a simultaneous and corresponding adjustment of the positioning elements and cutters, and means for operating the slides to move the cutters along edge portions of the plate.
- 20 25. A machine for trimming plates, including a cutter support, a pair of opposed slides movable thereon along substantially parallel lines, carriages mounted upon the slides and adjustable transversely thereof, cutters upon the carriages, means for continuously driving the cutters at all positions of the carriages, a carrier for moving the plate to the cutters, yieldably mounted positioning elements movable toward and away from each other and arranged to center a plate upon the carrier at a position distant from the cutters, means for retracting the positioning elements into inoperative position preparatory to moving the plate to the cutters, a manually operable adjusting element having an operative connection with both the positioning elements and the carriages for adjusting the cutters in a manner corresponding to the position of the positioning elements when the latter are in engagement with the plate, and means for operating the slides to move the cutters along edge portions of the plate.
- 25 30. A machine for trimming plates, including a feed table having an opening therein, a carrier block movable through the opening, oppositely moving slides on the feed table, plate positioning fingers carried by the slides and adapted to engage a plate to center it on the carrier, means for adjusting the slides for different sizes of plates, means for clamping the plate on the carrier, and
- 35 40. A machine for trimming plates, including a cutter support, a pair of opposed slides movable thereon along substantially parallel lines, carriages mounted upon the slides and adjustable transversely thereof, cutters upon the carriages, means for continuously driving the cutters at all positions of the carriages, a carrier for moving the plate to the cutters, yieldably mounted positioning elements movable toward and away from each other and arranged to center a plate upon the carrier at a position distant from the cutters, means for retracting the positioning elements into inoperative position preparatory to moving the plate to the cutters, a manually operable adjusting element having an operative connection with both the positioning elements and the carriages for adjusting the cutters in a manner corresponding to the position of the positioning elements when the latter are in engagement with the plate, and means for operating the slides to move the cutters along edge portions of the plate.
- 45 50. A machine for trimming plates, including a feed table having an opening therein, a carrier block movable through the opening, oppositely moving slides on the feed table, plate positioning fingers carried by the slides and adapted to engage a plate to center it on the carrier, means for adjusting the slides for different sizes of plates, means for clamping the plate on the carrier, and
- 55 60. A machine for trimming plates, including a feed table having an opening therein, a carrier block movable through the opening, oppositely moving slides on the feed table, plate positioning fingers carried by the slides and adapted to engage a plate to center it on the carrier, means for adjusting the slides for different sizes of plates, means for clamping the plate on the carrier, and
- 65 70. A machine for trimming plates, including a feed table having an opening therein, a carrier block movable through the opening, oppositely moving slides on the feed table, plate positioning fingers carried by the slides and adapted to engage a plate to center it on the carrier, means for adjusting the slides for different sizes of plates, means for clamping the plate on the carrier, and
- 75 80. A machine for trimming plates, including a feed table having an opening therein, a carrier block movable through the opening, oppositely moving slides on the feed table, plate positioning fingers carried by the slides and adapted to engage opposite sides of a plate to center it on the carrier, gearing for simultaneously moving the slides in opposite directions, means for adjusting the slides for different sizes of plates, means for clamping the plate on the carrier, and cutters for trimming the plate at another position of the carrier.
- 85 90. A machine for trimming plates, including a feed table having an opening therein, a carrier block movable through the opening, oppositely moving slides on the feed table, plate positioning fingers carried by the slides and adapted to engage opposite sides of a plate to center it on the carrier, yielding means normally tending to operate the slides to move the plate positioning fingers toward each other, means for moving the slides to retract the plate positioning fingers, means for clamping the plate on the carrier, and cutters for trimming the plate at another position of the carrier.
- 95 100. A machine for trimming plates, including a feed table having an opening therein, a carrier block movable through the opening, oppositely moving slides on the feed table, plate positioning fingers carried by the slides, gearing between the slides for causing them to move simultaneously in opposite directions, means for adjusting the slides for different sizes of plates, means for clamping the plate on the carrier, a corresponding pair of adjustably mounted cutters for trimming the plate at another position of the carrier, and means governed by the position of the positioning fingers for properly adjusting the cutters.
- 105 110. A machine for trimming plates, including a feed table having an opening therein, a carrier block movable through the opening, oppositely moving slides on the feed table, plate positioning fingers carried by the slides, means for causing the slides to move simultaneously in opposite directions, yielding means normally moving the slides to bring the positioning fingers into operative position, means for moving the slides to retract the positioning fingers, adjustable cutters for trimming the plate at another position of the carrier, and means governed by the position of the positioning fingers when in engagement with the plate to obtain a proper adjustment of the cutters.
- 115 120. A machine for trimming plates, including a feed table, a carrier block movable through the feed table, oppositely moving slides on the feed table, plate positioning fingers carried by the slides and adapted to engage a plate to center it on the carrier, means for adjusting the slides for different sizes of plates, means for clamping the plate on the carrier, and
- 125 130. A machine for trimming plates, including a feed table, a carrier block movable through the feed table, oppositely moving slides on the feed table, plate positioning fingers carried by the slides and adapted to engage a plate to center it on the carrier, means for adjusting the slides for different sizes of plates, means for clamping the plate on the carrier, and

cutters for trimming the plate at another position of the carrier.

27. A machine for trimming plates, including a feed table having an opening therein, a carrier block movable through the opening, oppositely moving slides on the feed table, plate positioning fingers carried by the slides and adapted to engage opposite sides of a plate to center it on the carrier, gearing for simultaneously moving the slides in opposite directions, means for adjusting the slides for different sizes of plates, means for clamping the plate on the carrier, and cutters for trimming the plate at another position of the carrier.

28. A machine for trimming plates, including a feed table having an opening therein, a carrier block movable through the opening, oppositely moving slides on the feed table, plate positioning fingers carried by the slides and adapted to engage opposite sides of a plate to center it on the carrier, yielding means normally tending to operate the slides to move the plate positioning fingers toward each other, means for moving the slides to retract the plate positioning fingers, means for clamping the plate on the carrier, and cutters for trimming the plate at another position of the carrier.

29. A machine for trimming plates, including a feed table having an opening therein, a carrier block movable through the opening, oppositely moving slides on the feed table, plate positioning fingers carried by the slides, gearing between the slides for causing them to move simultaneously in opposite directions, means for adjusting the slides for different sizes of plates, means for clamping the plate on the carrier, a corresponding pair of adjustably mounted cutters for trimming the plate at another position of the carrier, and means governed by the position of the positioning fingers for properly adjusting the cutters.

30. A machine for trimming plates, including a feed table having an opening therein, a carrier block movable through the opening, oppositely moving slides on the feed table, plate positioning fingers carried by the slides, means for causing the slides to move simultaneously in opposite directions, yielding means normally moving the slides to bring the positioning fingers into operative position, means for moving the slides to retract the positioning fingers, adjustable cutters for trimming the plate at another position of the carrier, and means governed by the position of the positioning fingers when in engagement with the plate to obtain a proper adjustment of the cutters.

31. A machine for trimming plates, including a feed table, a carrier block movable through the feed table, oppositely moving slides on the feed table, plate positioning fingers carried by the slides and adapted to engage a plate to center it on the carrier, means for adjusting the slides for different sizes of plates, means for clamping the plate on the carrier, and

- engage a plate to center it on the carrier, means for producing a simultaneous movement of the slides in opposite directions, a pair of adjustable cutters for trimming the plate at another position of the carrier, an adjusting shaft operatively connected to the cutters for moving the same toward and away from each other, and means whereby the adjustment of the cutters is governed by the position of the positioning fingers when the latter are in engagement with the plate to be trimmed.
32. A machine for trimming plates, including a feed table, a carrier movable through the feed table, oppositely moving slides on the feed table, plate positioning fingers carried by the slides, gearing for causing the slides to move simultaneously in opposite directions, yielding means for moving the slides to bring the positioning fingers into operative position, means for moving the slides to retract the positioning fingers into inoperative position, a pair of adjustable cutters for trimming the plate at a different position of the carrier, and a manually operable adjusting member operatively connected with the slides and cutters for obtaining a corresponding adjustment of the positioning fingers and cutters.
33. A machine for trimming plates, including a feed table, a carrier block movable through the feed table, a pair of oppositely moving slides on the feed table, positioning fingers carried by the slides and adapted to engage a plate to center it on the carrier, gearing for simultaneously moving the slides in opposite directions, an adjusting shaft, an operative connection between the adjusting shaft and the said gearing, a pair of adjustable cutters for trimming the plate at another position of the carrier, and an operative connection between the adjusting shaft and the cutters whereby the cutters are adjusted according to the position of the positioning fingers when the latter are in engagement with the plate to be trimmed.
34. A machine for trimming plates, including a feed table, a carrier movable through the feed table, a pair of oppositely moving slides mounted on the feed table, plate positioning fingers carried by the slides and adapted to engage a plate to center it upon the carrier, gearing for simultaneously moving the slides in opposite directions, an adjusting shaft, a block threaded upon the adjusting shaft and movable longitudinally thereon as the shaft is rotated, an operative connection between the block and the before mentioned gearing for moving the slides to adjust the positioning fingers, a pair of adjustable cutters for trimming the plate at another position of the carrier, and an operative connection between the adjusting shaft and the cutters for obtaining an adjustment of the cutters corresponding to the position of the positioning fingers when the latter are in engagement with the plate to be trimmed.
35. A machine for trimming plates, including a feed table, a carrier movable through the feed table, a pair of oppositely moving slides on the feed table, plate positioning fingers carried by the slides and adapted to engage a plate to center it on the carrier, an adjusting shaft, a nut threaded upon the adjusting shaft and movable longitudinally thereon as the shaft is rotated, a bar yieldably mounted upon the nut, means actuated by the movements of the bar to move the slides, means for moving the bar independently of the nut to retract the positioning fingers, a pair of cutters for trimming the plate at another position of the carrier, and an operative connection between the cutters and the adjusting shaft for obtaining a corresponding adjustment of the cutters and positioning fingers.
36. A machine for trimming plates, including a feed table, a carrier movable through the feed table, a pair of oppositely moving slides on the feed table, plate positioning fingers carried by the slides and adapted to engage a plate to center it on the carrier, a rack and pinion arrangement for simultaneously moving the slides in opposite directions, an adjusting shaft, a block threaded on the adjusting shaft and movable longitudinally thereon as the shaft is rotated, a bar slideable through the block and yieldably connected thereto, an operative connection between the bar and the rack and pinion arrangement for moving the slides, means for moving the bar independently of the block to retract the positioning fingers, a pair of cutters for trimming the plate at another position of the carrier, and an operative connection between the cutters and the adjusting shaft for adjusting the position of the cutters according to the position of the positioning fingers when the latter are in engagement with the plate.
37. A machine for trimming plates, including a feed table, a carrier movable through the feed table, a pair of oppositely moving slides mounted on the feed table, positioning fingers carried by the slides and adapted to engage the plate to center it on the carrier, racks carried by the slides, a pinion meshing with the racks to move the slides simultaneously in opposite directions, a shaft carrying the pinion, a second pinion on the shaft, an adjusting shaft, a rack bar engaging the second pinion and operatively connected with the adjusting shaft to be moved by the rotation thereof, a pair of adjustable cutters for trimming the plate at another position of the carrier, and an operative connection between the shaft and the

cutters for adjusting the position thereof to correspond to the position of the positioning fingers when the latter are in engagement with the plate to be trimmed.

- 5 38. A machine for trimming plates, including a feed table, a carrier movable through the feed table, oppositely moving slides mounted upon the feed table, plate positioning fingers carried by the slides and 10 adapted to engage the plate to center it on the carrier, an adjusting shaft, a rack bar operatively connected to the adjusting shaft so as to be actuated by the rotation thereof, a pinion engaged by the rack bar and operatively connected to the slides for simultaneously moving the same in opposite directions, a pair of cutters for trimming the plate at another position of the carrier, and an operative connection between the adjusting shaft and the cutters for adjusting the cutters to correspond to the position of the positioning fingers when the latter are in engagement with the plate to be trimmed.

39. A machine for trimming plates, including a feed table, a carrier movable through the feed table, a pair of oppositely moving slides mounted upon the feed table, plate positioning fingers carried by the slides and adapted to engage a plate to center it on the carrier, racks upon the slides, a pinion meshing with the rack for simultaneously moving the slides in opposite directions, a shaft carrying the pinion, a second pinion on the shaft, an adjusting shaft, a 30 block threaded on the adjusting shaft so as to be movable longitudinally thereof as the shaft is rotated, a rack bar yieldably mounted upon the block and meshing with the second pinion of the before mentioned shaft, 35 means for moving the rack bar independently of the block to retract the positioning fingers, a pair of adjustable cutters for trimming the plate at another position of the carrier, and an operative connection between the adjusting shaft and the cutters for adjusting the cutters to correspond to the position of the positioning fingers when the latter are in engagement with the plate to be trimmed.

40. A machine for trimming plates, including a feed table, a carrier movable through the feed table, a pair of oppositely moving slides mounted on the feed table, plate positioning fingers carried by the slides and adapted to engage a plate to center it on the carrier, gearing for causing the slides to move simultaneously in opposite directions, a pair of cutters for trimming the plate at another position of the carrier, adjusting means for the cutters, and a movable cam member mounted upon the adjusting means and arranged to coöperate with one of the before mentioned slides to obtain an adjustment of the cutters corresponding to

the position of the positioning fingers when the latter are in engagement with the plate to be trimmed.

41. A machine for trimming plates, including a feed table having an opening therein, a carrier movable through the opening, two sets of opposed positioning elements mounted upon the table and movable toward and away from each other for engagement with a plate to center it upon the carrier, two corresponding sets of opposed cutters for trimming the plate at another position of the carrier, and means controlled by the position of the positioning elements when in engagement with the plate to be trimmed for obtaining a corresponding adjustment of the two sets of cutters.

42. A machine for trimming plates, including a feed table having an opening therein, a carrier movable through the opening, two sets of opposed positioning elements arranged on opposite sides of the opening and movable toward and away from each other, said positioning elements being adapted to engage a plate to center it upon the carrier, two sets of oppositely moving slides carrying the respective positioning elements, manually operated members for independently adjusting the two sets of slides, two sets of adjustable cutters for trimming the plate at another position of the carrier, the cutters of each set being movable toward and away from each other, and operative connections between the manually operable adjusting members and the respective sets of cutters for adjusting the positions of the cutters to correspond with the positions of the positioning elements when the latter are in engagement with a plate to be trimmed.

43. A machine for trimming plates, including a feed table having an opening therein, a carrier movable through the feed table, two sets of opposed positioning elements movable toward and away from each other and arranged on opposite sides of the opening, said positioning elements being adapted to engage a plate to center it upon the carrier, two sets of oppositely moving slides carrying the respective sets of positioning fingers, means for causing the slides of each set to move simultaneously in opposite directions, independent means for adjusting the two sets of slides and positioning fingers, two sets of adjustable cutters for trimming the plate at another position of the carrier, and means for adjusting the cutters to correspond with the position of the corresponding positioning elements when the latter are in engagement with a plate to be trimmed.

44. A machine for trimming plates, including a feed table having an opening therein, a carrier movable through the opening, two sets of opposed positioning elements arranged upon opposite sides of the

- opening and movable toward and away from each other, said positioning elements being adapted to engage a plate to center it on the carrier, two sets of oppositely moving 5 slides carrying the respective sets of positioning fingers, an operative connection between the slides of each set for causing them to move simultaneously in opposite directions, two corresponding sets of adjustable 10 cutters for trimming the plate at another position of the carrier, two manually operable adjusting shafts operatively connected with the respective sets of cutters for adjusting the positions thereof, and means 15 operating with the said adjusting means for gaging the adjustment of the cutters to correspond to the position of the positioning elements when the latter are in engagement with the plate.
- 20 45. A machine for trimming plates, including a feed table having an opening therein, a carrier movable through the opening, two sets of opposed positioning elements movable toward and away from each 25 other and arranged upon opposite sides of the opening, said positioning elements being adapted to engage the plate to center it upon the carrier, two sets of oppositely moving slides carrying the respective sets of positioning elements, gearing between the slides of each set for causing them to move corresponding amounts in opposite directions, yielding means normally tending to move 30 the positioning elements into engagement with the plate, means for retracting the positioning elements, two opposed sets of adjustable cutters for trimming the plate at another position of the carrier, manually 35 movable adjusting elements operatively connected with the respective sets of cutters for moving the same toward and away from each other, and means coöperating with the adjusting means and controlled by the position 40 of the positioning elements when the latter are in engagement with the plate to obtain the proper adjustment of the cutters.
46. A machine for trimming plates, including a feed table, a swinging carrier movable through the feed table, positioning means 50 mounted upon the feed table for engagement with the plate to center it upon the carrier, cutters for trimming the plate at another position of the carrier, a shaft, and cam means actuated by the shaft for 55 clamping the plate upon the carrier, moving the carrier to the cutters, releasing the plate, and returning the carrier to its original position, in sequence.
47. A machine for trimming plates, including a feed table, a carrier movable through the feed table, positioning means 60 upon the feed table for centering a plate on the carrier, cutters mounted to trim the plate at another position of the carrier, a
- cam shaft, and means actuated by the cam 65 shaft for clamping the plate upon the carrier, moving the carrier to the cutters, releasing the plate, returning the carrier to its original position, and stopping the machine, in sequence. 70
48. A machine for trimming plates, including a feed table, a carrier movable through the feed table, positioning means upon the feed table for centering a plate upon the carrier, cutters for trimming the plate at another position of the carrier, said 75 cutters being slidably rectilinearly of the plate, a shaft, and cam means actuated by the shaft for clamping the plate upon the carrier, moving the carrier to the cutters, 80 moving the cutters rectilinearly of the plate, releasing the plate, and returning the carrier to its original position, in sequence.
49. A machine for trimming plates, including a feed table, a carrier movable through the feed table, positioning means mounted upon the feed table for centering a plate upon the carrier, rectilinearly movable cutters for trimming the plate at another 85 position of the carrier, a shaft, a clutch controlling the operation of the shaft, and cam means actuated by the shaft for clamping the plate upon the carrier, moving the carrier to the cutters, moving the cutters rectilinearly, releasing the plate, returning 90 the carrier to its original position, and opening the clutch, in sequence.
50. In a machine for trimming plates, the combination of a feed table, a carrier movable through the feed table, yieldably mounted 95 positioning means upon the feed table for centering a plate upon the carrier, cutters for trimming the plate at another position of the carrier, a drive shaft, a cam shaft, a clutch control connection between the drive shaft 100 and the cam shaft, a clutch closing member, means preventing actuation of the clutch closing member until the positioning elements have been retracted from the path of the feed table, and cam means actuated by the cam 105 shaft for clamping the plate upon the carrier, moving the plate to the cutters, releasing the plate, and returning the carrier to its original position.
51. A machine for trimming plates, including a feed table, a carrier movable through the feed table, yieldably mounted 110 positioning elements upon the feed table to center a plate upon the carrier, cutters for trimming the plate at another position of the carrier, a drive shaft, a cam shaft having a clutch controlled connection with the drive shaft, a clutch operating lever, a slide mounted upon the lever, means actuated by the slide for retracting the positioning fingers away from the path of the carrier, and cam means actuated by the cam shaft for 115 clamping the plate upon the carrier, moving the plate to the cutters, releasing the plate, and returning the carrier to its original position.
52. A machine for trimming plates, including a feed table, a carrier movable through the feed table, yieldably mounted 120 positioning elements upon the feed table to center a plate upon the carrier, cutters for trimming the plate at another position of the carrier, a drive shaft, a cam shaft having a clutch controlled connection with the drive shaft, a clutch operating lever, a slide mounted upon the lever, means actuated by the slide for retracting the positioning fingers away from the path of the carrier, and cam means actuated by the cam shaft for 125 clamping the plate upon the carrier, moving the plate to the cutters, releasing the plate, and returning the carrier to its original position.

the carrier to the cutters, releasing the plate, and returning the carrier to its original position.

52. A machine for trimming plates, including a feed table, a carrier movable through the feed table, retractable positioning means upon the feed table for centering a plate upon the carrier, cutters for trimming the plate at another position of the carrier, a drive shaft, a cam shaft having a clutch controlled connection with the drive shaft, a clutch operating lever, a slide on the lever, means actuated by the slide for retracting the positioning elements from the path of the carrier, and cam means actuated by the shaft for clamping the plate upon the carrier, moving the carrier to the cutters, moving the cutters rectilinearly along the edges of the plate, releasing the plate, and returning the carrier to its original position.

53. A machine for trimming plates, including a feed table, a carrier movable through the feed table, retractable positioning elements mounted upon the feed table for centering a plate upon the carrier, cutters for trimming the plate at another position of the carrier, a drive shaft, a cam shaft having a clutch controlled connection with the drive shaft, a lever for operating the clutch, a slide mounted upon the lever, an operative connection between the slide and the positioning fingers for retracting the same from the path of the carrier, means for preventing movement of the lever until the slide has been actuated, and cam means actuated by the lever for clamping the plate upon the carrier, moving the carrier to the cutters, releasing the plate, and returning the carrier to its original position.

54. A machine for trimming plates, including a feed table, a carrier movable through the feed table, retractable positioning elements mounted upon the feed table and adapted to engage the plate to center it upon the carrier, cutters for trimming the plate at another position of the carrier, a cam shaft, a drive shaft having a clutch control connection with the drive shaft, a lever controlling the clutch, a member carried by the lever and operable thereon, said member having an operative connection with the positioning elements for retracting them from the path of the carrier, means for preventing movement of the lever until the said member has been actuated, and cam means actuated by the cam shaft for locking the plate upon the carrier, moving the carrier to the cutters, releasing the plate, returning the carrier to its original position, and opening the clutch.

55. A machine for trimming plates, including a feed table, a swinging carrier provided with a block which is movable through the feed table, retractable positioning elements upon the feed table for engaging a

plate and centering it upon the carrier block, cutters for trimming the plate at another position of the carrier, means for retracting the positioning elements from the path of the carrier, a cam shaft, a plate pivoted concentric with the carrier and operatively connected to the cam shaft, means controlled by the plate for locking the plate upon the carrier at one position thereof and releasing the plate at another position of the carrier, and cam means also actuated by the shaft for moving the carrier to swing the block toward and away from the cutters.

56. A machine for trimming plates, including a feed table, a swinging carrier formed with a block movable through the feed table, positioning elements upon the feed table for centering a plate upon the carrier block, cutters for trimming the plate at another position of the carrier block, a rock shaft mounted upon the swinging end of the carrier, a plate pivoted concentric with the carrier, an operative connection between the plate and the rock shaft, clamping means controlled by the rock shaft, a cam shaft operatively connected to the plate and controlling the clamping means, and means also actuated by the cam shaft for swinging the carrier frame into and out of cutting position.

57. A machine for trimming plates, including a feed table, a swinging carrier provided with a carrier block movable through the feed table, positioning means upon the feed table for centering a plate upon the carrier block, cutters for trimming the plate at another position of the carrier block, a plate pivoted concentric with the carrier and provided with a pair of lugs, a lever pivoted concentric with the plate and having one end thereof received between the lugs so as to be in engagement with one lug in one position of the carrier, and in engagement with the other lug at another position of the carrier, clamping means controlled by the lever, a cam shaft having an operative connection with the plate, and means also actuated by the cam shaft for swinging the carrier to move the carrier block toward and away from the cutters.

58. A machine for trimming plates, including a feed table, a swinging carrier provided with a carrier block movable through the feed table, positioning means upon the feed table for centering a plate upon the carrier block, cutters for trimming the plate at another position of the carrier block, a plate pivoted concentric with the carrier and provided with a pair of lugs, a lever pivoted concentric with the plate and having one end thereof received between the lugs so as to engage one lug at one position of the carrier and another lug at another position of the carrier, a rock shaft mounted upon the swinging end of the

carrier and operatively connected to the lever, clamping means controlled by the rock shaft, a cam shaft operatively connected to the pivoted plate and coöperating there-
5 with to clamp and release the plate being trimmed, and means for swinging the carrier to move the carrier block toward and away from the cutters.

59. A machine for trimming plates, in-
10 cluding a feed table, a swinging frame pro-
vided with spaced end pieces, a carrier block
mounted upon one end piece and movable
through the feed table, a clamping block
mounted upon the other end piece in an op-
15 posed relation to the carrier block, position-
ing means for centering the plate upon the
carrier block, means for clamping the plate
between the carrier block and the clamping
block, cutters for trimming the plate at an-
20 other position of the carrier, a cam shaft
controlling the clamping action, and means
also actuated by the cam shaft for swinging
the carrier block toward and away from the
cutters.

25 60. A machine for trimming plates, in-
cluding a feed table, a swinging carrier formed
with opposed end pieces, a carrier block
mounted upon one end piece and movable
30 through the feed table, an opposed
clamping block mounted upon the other end
piece, positioning means for centering a
plate upon the feed block, means for clamp-
ing the plate between the feed block and
35 clamping block, cutters for trimming the
plate at another position of the carrier, a
plate pivotally mounted concentric with the
carrier and controlling the clamping action,
a cam shaft operatively connected to the
40 plate, and means for swinging the carrier
to move the plate toward and away from the
cutters.

61. A machine for trimming plates, in-
cluding a feed table, a swinging carrier pro-
vided with opposed end pieces, a carrier
45 block movably mounted upon one end piece,
an opposed clamping block mounted upon
the other end piece, positioning means for
centering a plate upon the carrier block,
means for moving the carrier block toward
50 the clamping block to clamp the plate in
position between the elements, a plate piv-
oted concentric with the carrier, means actu-
ated by the plate for moving the carrier
block toward and away from the clamping
55 block, means for actuating the pivoted plate
to clamp and release the plate at proper in-
tervals of time, and means for swinging the
carrier to move the block toward and away
from the cutters.

60 62. A machine for trimming plates, in-
cluding a feed table, a swinging carrier pro-
vided with opposed end pieces, a carrier
block slidably mounted upon one end piece
and movable through the feed table, a

clamping block mounted upon the other end 65
piece and having an opposed relation to the
carrier block, means for centering a plate
upon the carrier block, cutters for trim-
ming the plate at any position of the carrier
block, a rock shaft upon the swinging end 70
of the carrier, toggle means actuated by the
rock shaft for moving the carrier block to-
ward and away from the clamping block, a
pivoted plate mounted concentric with the
carrier and operatively connected to the rock 75
shaft, means for actuating the pivoted plate
to clamp and release the plate to be trimmed,
and means for swinging the carrier to move
the carrier block toward and away from the
cutters. 80

63. A machine for trimming plates, in-
cluding a set of cutters arranged in an in-
clined plane, a carrier for bringing a plate
to the cutters, and an inclined discharge
chute receiving the trimmed plate from the 85
carrier, the portion of the chute adjacent
to the carrier and initially receiving the plate
therefrom being yieldably mounted.

64. A machine for trimming plates, in-
cluding a set of cutters arranged in an in-
clined plane, a carrier for bringing the plate
90 to the cutters, and an inclined chute ar-
ranged under the cutters for the discharge
by gravity of the trimmed plate and cut-
tings, the chute being formed with open 95
spaces through which the cuttings fall while
the plate slides down the chute.

65. A machine for trimming plates, in-
cluding a set of cutters arranged in an in-
clined plane, a carrier for bringing the plate 100
to the cutters, an inclined chute arranged
under the cutters and providing for the dis-
charge of gravity of the chips and trimmed
plates, the bottom of the chute being formed
105 with openings through which the chips drop,
and a pocketed carrier receiving the
trimmed plates from the inclined chute and
movable in synchronism with the first men-
tioned carrier.

66. A machine for trimming plates, in-
cluding a plate supporting member, means
for clamping the plate upon the plate sup-
porting member, and cutters for simulta-
110 neously trimming all of the edges of the
plate while it is clamped upon the plate sup-
porting member.

67. A machine for trimming plates, in-
cluding a movable cutter for each edge of
the plate, a carrier for bringing the plate
115 to the cutters, and means for moving the
cutters rectilinearly of the plate to trim all
of the edges thereof simultaneously.

68. A machine for trimming plates, in-
cluding a movable cutter for each edge of
the plate, said cutters being arranged in an 120
inclined plane, a carrier for bringing the
plate to the cutters, means for moving the
cutters rectilinearly of the plate to trim all

of the edges thereof simultaneously, and gravity discharge means for the trimmed plates and chips.

69. A machine for trimming plates, including a series of movable cutters arranged in an inclined plane, one cutter being provided for each edge of the plate to be trimmed, a carrier for bringing the plate to the cutters, means for clamping the plate

upon the carrier, an inclined chute receiving the chips and trimmed plates and discharging them by the action of gravity, and means for releasing the plate after it has been trimmed.

In testimony whereof I have signed my name to this specification.

JACOB SIMPSON.
